UNITED STATES PATENT OFFICE.

ALBERT J. ELDON, OF MONTCLAIR, NEW JERSEY, ASSIGNOR TO PARAMOUNT RUBBER CONSOLIDATED, INC., OF LITTLE FALLS, NEW JERSEY, A CORPORATION OF DELAWARE.

DESIGN FOR A BALL.

Application filed February 15, 1923. Serial No. 5,178. Term of patent 14 years.

To all whom it may concern:

Be it known that I, ALBERT J. ELDON, of the ball; Fig. 2 is a fragmentary cross a citizen of the United States, residing at section thereof through one of the poles, as Montclair, in the county of Essex and State indicated by the line 2—2 on Fig. 1.

of New Jersey, have invented a new, original, and ornamental Design for a Ball, of which the following is a specification, reference being had to the accompanying drawings, forming a part thereof.

I claim:

The ornamental design for a ball substantially as shown in the drawings hereof.

ALBERT J. ELDON.
